UNITED STATES PATENT OFFICE.

CLARENCE G. A. STEINHEISER, OF OIL CITY, PENNSYLVANIA.

COMBINED I-BEAM AND RAIL-CLAMP.

1,299,868.

Specification of Letters Patent. Patented Apr. 8, 1919.

Application filed March 8, 1918. Serial No. 221,124.

To all whom it may concern:

Be it known that I, CLARENCE G. A. STEINHEISER, a citizen of the United States, residing at Oil City, in the county of Venango, State of Pennsylvania, have invented 5 a new and useful Combined I-beam and Rail-Clamp; and I do hereby declare the following to be a full, clear, and exact description of the invention, such as will enable others skilled in the art to which it appertains to make and use the same.

This invention relates to an improved rail clamp, and one of the objects of the invention is to provide a simple and improved 15 device of this kind, which may be manufactured for a small cost and sold at a reasonable profit.

A further object of the invention is to provide clamping members having connections with an I-beam, one clamping member on each side of the base of the rail, for 20 clamping the rail securely in position.

A further object of the invention is to provide a locking key for holding the clamping plate in place, in combination with a 25 cotter pin for locking the key in position.

In practical fields the details of construction may necessitate alterations falling within the scope of what is claimed.

The invention comprises further features and combination of parts as hereinafter set forth shown in the drawings and claimed.

In the drawings:—

Figure 1 is a view in perspective of the 35 improved rail clamping device constructed in accordance with the invention.

Fig. 2 is a plan view showing the web of the rail in section.

Fig. 3 is a sectional view on line 3—3 of 40 Fig. 2.

Fig. 4 is a view in side elevation of a portion of the I-beam showing the rail in section, and being clamped to the I-beam by means of the improved clamping device.

Referring more especially to the drawings, 45 1 designates an I-beam, the top of which is provided with apertures 2 and 3. The aperture 2 is arranged diagonally to the aperture 3. Rail clamping plates 5 and 6 are provided. These plates are each 50 similarly constructed. Each edge portion of each clamping plate is undercut, to provide the angular recess 7 and the overhanging flange 8. In holding a rail in place, each 55 one of the sides of the base of the rail may engage the recess 7, whereby the overhang-

ing part 8 may overlie the base of the rail, which base of the rail is designated by the numeral 9. Each clamping plate is provided with an aperture 10, for the reception of a 60 headed pin 11, which is designed to enter either one of the apertures 2 and 3 of the I-beam, it depending entirely, on which side of the rail the clamping plate is arranged, and what position the clamping plate may 65 assume. The clamping plate 5 is on one side of the rail, and the clamping plate 6 is adjacent the opposite side of the rail. In this case the pin 10 of the plate 5 engages the innermost aperture 2 of the I-beam 1, and 70 the pin 10 of the clamping plate 6 engages the innermost aperture 3 of the I-beam. However, the clamping plate 5, it is to be noted may be adjusted so that the pin 11 75 may pass through the outermost aperture 2 of the I-beam. If desired the clamping plate 6 may be disposed whereby its headed pin 11 may engage the outermost aperture 3 of the I-beam. One end of each clamping plate has an undeturned hook 12, to engage 80 under the flange of the I-beam. The other end of each clamping plate is also provided with a hook 13 extending in a position under the opposite flange of the I-beam. However, the under protruding part of the 85 hook 13 is spaced from the under face of the flange of said I-beam. It is to be noted that in spacing the under protruding part from the under surface of the flange of the I-beam, a recess 14 is constructed or caused 90 to be formed, and the upper wall 15 of this recess 14 is inclined with relation to the lower wall, in fact inclined in alignment with the underface of the flange 16 of the I-beam. Each clamping plate has a shoulder 95 17, between which and the wall 18 of the under protruding hook 12, the opposite portions of the flange 16 of the I-beam engages. It is to be noted that the recess 14 is somewhat V-shaped, and is designed to receive a 100 key 19 which is V-shaped in cross section, in fact correspondingly shaped in cross section to conform to and enter said recess. The head end 20 of the key protrudes laterally, hence providing a shoulder 21, which 105 engages one side of the hook member 13, to prevent movement of the key in one direction. A cotter pin 22 extends through an aperture 23 in the smaller end of the key between the part 13 and the edge of the base 110 of the rail, thereby preventing movement of the key in the opposite direction. The

headed pin 11 acts to prevent movement of the clamping plate. It is to be observed that the key 19 is wide enough, so as to underlie the top flange 16 of said I-beam, so as to prevent upward movement of the clamping plate. It being noted that there are two of the clamping plates, one on each side of the rail, each having its overhanging portion 8 engaging the base of the rail, the rail is held securely in place and against lateral movement, and it is to be further noted that either one of the overhanging parts 8 of either clamping plate may be employed.

The invention having been set forth what is claimed as new and useful is:

1. In combination, an I-beam, a rail engaging thereon, a clamping plate, one end of the plate having means extending under the top flange of the I-beam, the other end 20 of the clamping plate having an under protruding hook underlying and spaced from the bottom of the opposite part of the top flange of the I-beam, said hook portion having an adjoining recess V-shaped in cross section, a key engaging said recess and underlying the top flange of the I-beam, means to prevent movement of the key in either direction, said clamping plate having means on each of its opposite edges to overlie the 30 base of the rail to hold the rail in position.
2. In combination, an I-beam, a rail engaging thereon, a clamping plate, one end of the plate having means extending under the top flange of the I-beam, the other end 35 of the clamping plate having an under protruding hook underlying and spaced from the bottom of the opposite part of the top flange of the I-beam, said hook portion having an adjoining recess V-shaped in cross section, a key engaging said recess and underlying the top flange of the I-beam, one end of the key having a shoulder to engage one edge portion of the clamping plate to prevent movement of the key in one direction, a cotter pin engaging the other end of 40 the key in the path of the opposite edge part of the plate to prevent movement of the key in the opposite direction, said clamp-

ing plate having means on each of its opposite edges to overlie the base of the rail to hold the rail in position, and means for holding the plate against movement on the I-beam.

3. In combination, an I-beam, a rail engaging thereon, interchangeable and reversible clamping plates on the I-beam, one on each side of the rail to hold the same in place, means carried on either edge of each plate to overlie the base of the rail, means to prevent movement of the plate longitudinally of the I-beam, a hook at one end of the plate to underlie one edge of the flange of the I-beam, and locking means for the other end of the plate.

4. The combination with an I-beam, of a rail engaging thereon, a clamping plate on the I-beam adjacent each side of the rail and having a flange overlying the base of the rail, one end of the clamping plate having connections with one edge of the top flange 70 of the I-beam, the other end of the clamping plate having an under protruding hook underlying and spaced from the bottom of the opposite part of the top flange of the I-beam, said hook portion having an adjoining key 75 receiving recess, a V-shaped key engaging said recess and being disposed under the top flange of the I-beam, one end of the key having a lateral abutment engaging one edge portion of the clamping plate to prevent movement of the key in one direction, means detachably engaging the other end of the key and being disposed in the path of the opposite edge of the plate to prevent movement of the key in the opposite direction, and means for holding the clamping plate against movement longitudinally on the I-beam.

In testimony whereof I have signed my name to this specification in the presence of 90 two subscribing witnesses.

C. G. A. STEINHEISER.
